UNITED STATES PATENT OFFICE

90,895

DESIGN FOR A FOUNTAIN PEN

George Miller, Sr., Marion, Iowa

Application January 16, 1932. Serial No. 42,514

Term of patent 7 years

To all whom it may concern:

Be it known that I, GEORGE MILLER, SR., a citizen of the United States, residing at Marion, in the county of Linn and State of Iowa, have invented a new, original, and ornamental Design for Fountain Pens, of which the following is a specification, reference being had to the accompanying drawing, forming part thereof.

Figure 1 is a front elevation of a fountain pen, in an open position, showing my new design; and

I claim:

The ornamental design for a fountain pen, as shown.

In witness whereof, I hereunto subscribe my name this eleventh day of January, 1932.

GEORGE MILLER, SR.
